UNITED STATES PATENT OFFICE

139,175

DESIGN FOR A POWDER BOX

James M. Downs, Detroit, Mich.

Application July 29, 1944, Serial No. 114,624

Term of patent 14 years

(Cl. D86—10)

To all whom it may concern:

Be it known that I, James M. Downs, a citizen of the United States, residing at Detroit, in the county of Wayne and State of Michigan, have invented a new, original, and ornamental Design for a Powder Box, of which the following is a specification, reference being had to the accompanying drawings, forming part thereof,

Figure 1 is a side elevational view of a powder box showing my new design,

Figure 2 is a top plan view, and
Figure 3 is a bottom plan view thereof.
Figure 4 is a side elevational view of the powder box in exploded position.

I claim:
The ornamental design for a powder box, as shown.

JAMES M. DOWNS.
